(57) **CLAIM**

The ornamental design for surgical tool, as shown and described.

DESCRIPTION

FIG. 1 is a side view of the surgical tool, the opposite side view being a mirror image;

FIG. 2 is a front end view thereof;

FIG. 3 is a rear end view thereof;

FIG. 4 is a top view thereof; and,

FIG. 5 is a bottom view thereof.

The broken line showing in FIGS. 1 through 5 are for illustrative purposes only and forms no part of the claimed design.
